UNITED STATES PATENT OFFICE.

NESTOR FRERE, OF LONDON, COUNTY OF MIDDLESEX, ENGLAND.

COMBINATION WATCH-CHAIN AND PEN AND PENCIL HOLDER.

SPECIFICATION forming part of Letters Patent No. 367,804, dated August 9, 1887.

Application filed January 27, 1886. Serial No. 189,897. (No model.) Patented in France October 27, 1885, No. 171,908; in England December 9, 1885, No. 15,142, and in Germany December 28, 1885, No. 36,575.

To all whom it may concern:

Be it known that I, NESTOR FRERE, a subject of the Queen of Great Britain, residing at No. 13 Upper Westbourne Terrace, London, 5 in the county of Middlesex, England, engineer, have invented a new and useful Combination Watch-Chain and Pen and Pencil Holder, (for which Letters Patent have been granted in the following countries: Great Britain, No. 15,142, 10 December 9, 1885; France, No. 171,908, October 27, 1885; and Germany, No. 36,575, December 28, 1885,) of which the following is a specification.

My invention relates to an improved combination watch-guard and pen and pencil holder; and it consists in making the links of the watch-guard mutually telescopic, so that by being made to close up by sliding over or into each other the flexible and pendent guard is 20 immediately converted into a rigid pen or pencil holder. A light chain runs through the series of telescopic links to which it is loosely connected. Each guard is furnished with a small ink-bottle, which can be conveniently 25 produced so as to serve the purpose of a seal, the pencil or pen being preferably at the watch end of the guard. The guard is made detachable from both watch and wearer by means of snap-hooks or other equivalent device.

30 I attain the object of my invention by the mechanism illustrated in the accompanying drawings, in which—

Figure 1 is an elevation of a combination watch-guard made according to my invention, 35 detached, and closed up, thereby producing a pen-holder. Fig. 2 is a sectional elevation of two adjoining links closed up, and Fig. 3 is a sectional elevation of two adjoining links disjoined as the links would be when my invention is being used as a watch-guard. Fig. 4 40 shows a combination-guard made as a pen-holder disconnected, with the pen reversed, the ink-bottle closed, and ready for receiving the watch and to be attached to the vest.

45 Like letters are marked throughout the figures with the same reference-letter.

A A are the links or tubes, between each pair of which I interpose a smaller one, B, of about the same length, but of a proper diameter at 50 its ends for sliding evenly, but not loosely, within the ends of the tubes A A. Rings or

projections b b are formed upon the tubes B B, to prevent them being pushed too far into the tubes A A, as well as to add to the rigidity of the holder.

55 Although the figures illustrate the tubes A B as of a circular section, I wish it to be distinctly understood that I do not confine myself to this section, nor to the exact outer conformation of the tubes, inasmuch as any outline or conformation may be given to them, according to the taste or fancy of the manufacturer, provided that the ends of the smaller links are capable of sliding into the larger ones evenly, but not loosely.

60 C is a plain chain longer than the total number of tubes A B, which are threaded upon it, the center of a link of this chain preferably coinciding with the center of a tube, as shown in Fig. 3. A pin, c, is passed through the 70 center of each tube and through a link of the chain C. The play of the tubes A and B is therefore limited and the continuity of the guard maintained. One end of the chain C 75 may conveniently terminate in a snap-hook, D, forming a flexible and convenient connection with the bar d or its equivalent.

80 E is a small ink-reservoir hanging from its cap e, which is connected to the end of the chain or of the guard. The other end of the chain is fastened to the terminal tube A', which is preferably longer than the tubes A. It receives a reversible pen-holder, F, or a pencil-holder may be substituted. The connection with the watch is effected by means of a snap-hook, F', or equivalent device.

85 I do not confine myself to fitting the terminal F with a single pen or a single pencil, inasmuch as a reversible terminal having a pen at one end and a pencil at the other may be 90 used.

95 The mode of using my invention is as follows: If the wearer wishes to use the pencil only, he detaches the snap-hook F' from his watch, leaving the latter in his pocket, and the closing up of as many tube-links as may be considered necessary produces a practicable pencil-holder. When the wearer has finished, he separates the links by pulling the ends of the chain C and re-attaches his watch. 100 The use of the pencil does not require so many tube-links to be closed up as would be neces-

sary to form a practicable pen-holder, inasmuch as the grip necessary to use a pen properly cannot be conveniently gained upon a length which is quite sufficient to furnish a practicable pencil. When it is required to use a pen, the watch is disconnected, the terminal F adjusted, the chain taken off the snap D, and closed up. This produces a practicable pen-holder. The ink-bottle E is unscrewed from its cap, or the latter may be made detachable.

I claim—

1. A watch-guard consisting of tubes the ends of which are of different diameters, the external diameter of the ends of the smaller tubes being equal to the internal diameter of the ends of the larger, and which tubes are strung alternately upon a chain, to the links of which they are severally connected, substantially as and for the purpose described with reference to the accompanying figures.

2. In a watch-guard, the combination of tubes having ends of different diameters, the external diameter of a small end being equal to the internal diameter of a large end, a chain upon which all the tubes are strung alternately, a small end next to a large one, with transverse pins fixed diametrically in the tubes and passing through links in the chain, substantially as and for the purpose described with reference to the accompanying drawings.

3. In a watch-guard, the combination, with tubes of different diameters, of rings upon the smaller tubes at a short distance from the ends of the same, which rings are approximately of the same diameter and shape as the end of the larger tubes, against which they abut when the ends of the smaller tubes are pushed into the ends of the larger ones, substantially as and for the purpose described with reference to 40 the accompanying drawings.

4. The combination, with a watch-guard made of tubes of different diameters, the external diameter of the ends of the smaller being equal to the internal diameter of the adjoining larger tubes strung upon a chain, to which they are severally connected, of a pendant with bottle and movable pen or pencil end, substantially as and for the purpose described with reference to the accompanying 50 drawings.

In witness whereof I have hereunto set my hand this 7th day of January, 1886.

NESTOR FRERE.
